APPARATUS FOR MOLDING PIPE

Edward F. Stratton, Spring City, Pa.

Application April 8, 1933. Serial No. 665,165

4 Claims. (Cl. 22—126)

This invention relates to new and useful improvements in molding apparatus and has particular relation to molds of a permanent character especially designed to be used in casting 5 iron or other metallic piping.

The principal object of the invention is to provide molding apparatus of the general character set forth having a mold provided with novel means for centering a core spindle within 10 said mold.

Another object of the invention is to provide molding apparatus of the general character set forth having a core spindle provided with grooves on the surface thereof to insure adhesion of the 15 customary silica sand core surface thereto.

Another object of the invention is to provide molding apparatus of the general character set forth which is of simple construction yet strong and durable and highly practical from the stand- 20 point of manufacture and use.

A more specific object of the invention is to provide molding apparatus of the general character set forth wherein pipe or other structures may be cast and subsequently used without spe- 25 cial cleaning or other finishing operations.

Certain other features and details of the invention are disclosed hereinafter and shown in the accompanying drawings, in which:

Figure 1 is a view in elevation of the mold 30 contemplated by the present invention;

Fig. 2 is a view in plan of the disclosure in Fig. 1;

Fig. 3 is an end elevation of the disclosure in Fig. 1; and

Fig. 4 is a view in section on line 4—4, Fig. 3.

It is generally known that in casting pipe and like structures and it is desirable to use permanent molds of metal by reason of the fact that castings made therein are of inherently 40 greater tensile and crushing strength than can be produced in the ordinary sand or other de- structible molds.

Referring now more particularly to the drawings, a permanent mold designated generally as 45 A, comprises cope and drag sections 1 and 2 respectively which are of substantially semi-an- nular cross section shape having bell and spigot molds 3 and 4 at its opposite ends. In the pres- ent instance the sections of the mold are pivot- 50 ally connected to each other at their lower edges by means of hinges 5 and suitable locking devices 6 are mounted at the upper edges of each of said sections for the purpose of se- curing the mold in closed position as shown in 55 the drawings. As will be noticed a plurality of

recesses of different configuration are formed in the abutting surfaces at the top of each mold section 1 and 2 and are suitably positioned longitudinally thereof so that when the flask is closed, each recess in the drag section 2 will co- 60 operate with a corresponding recess in the cope 1 to form pouring gates and gas vents 7 and 8 respectively.

The drag section 2 of the mold A is permanently secured in supporting cradles 9 which 65 extend rearwardly below said mold section and are provided with upstanding supports or bracket portions 10. A pulley 11 is rotatably journaled at the upper end of each of the upstanding brackets 10; and this pulley is grooved as 70 at 12 to receive a rope or other pull means 13. The forward end of the pull means 13 is secured to an eye bolt or other similar means 14 mounted on the cope section 1 of the mold adjacent the upper longitudinal edge of the latter, and the opposite end of said pull means 75 has a counter weight 15 attached thereto, the purpose for which will be set forth hereinafter.

The customary core is provided and comprises a hollow spindle 16 having a peripheral layer or 80 covering of silica sand or other equally suitable material 17. In the present instance and in order that the layer of silica sand will better adhere to the periphery of the spindle 16, the surface of the latter is provided with a series of helical grooves 85 18, each of which intercept another of said grooves at a plurality of points throughout the length of the spindle. It will be obvious that the grooves 18 formed on the surface of the spindle 16 will be filled with silica sand as shown in Fig. 4 of 90 the drawings, and key the layer or covering securely on the spindle. A plurality of vents 19 extend radially through the hollow spindle 16 at each junction of the helical grooves 18 so that gases accumulating at the inner side of the pipe 95 or like article being cast, may escape through the pores in the layer of silica sand and the vents 19 to the interior of the spindle 16 which is open at its ends to the atmosphere. In use, the spindle or tube 16 is coated with silica sand until the 100 core is of proper diameter and shape, and the core is then baked before placing the latter in the flask.

In the present instance the core B is supported in the mold by means of asbestos rings 20 which 105 are mounted in undercut grooves 21 formed circumferentially in the inner wall of the mold between each end of the flask cavity and the adjacent ends of said mold. As will be noticed by referring to Fig. 4 of the drawings, clearance is 110

provided between the end surfaces of the core 16 and the surrounding end portions of the mold to allow a certain amount of flexibility or play so that the asbestos rings 20 may be compressed as the mold sections come together, whereby the core B is centered concentrically in said mold. Of course, the extent of compression of the rings 20 will vary at different portions thereof and when the mold is finally locked in closed position the core will be positioned concentrically within the mold ready for casting. In addition to the above the asbestos rings 20 function to prevent seepage longitudinally of the core of any of the molten metal entering the mold inwardly of the gates 7.

With the core B thus positioned within the mold A and the locking devices 6 clamped to secure the mold sections in closed position, molten metal may be poured into said mold through the pouring gates 7 and a pipe or other like article cast therefrom. When the mold is poured, the heat of the molten metal causes the coating of sand to disintegrate so that the core spindle 16 may be readily withdrawn from the mold.

When the casting operation is completed and the clamps or locking means 6 are released to permit separation or opening of the mold sections, the cope section 1 of the flask may be swung with the aid of the counterweight 15 to the position shown in dotted lines in Fig. 3, and the cast pipe removed therefrom. It should be particularly understood that a pipe or similar article cast in apparatus of the character set forth need not be subsequently cleaned in a rumbler or other device in the customary manner as the use of a metal mold and the novel construction of the vents in the latter and the core spindle 16 allow immediate diffusion of accumulated gases during the casting operation, and a perfect casting may be produced. When the finished casting has been re-

moved from the mold, another core may be inserted and concentrically positioned within the mold by rings 20 for successive casting operations to be performed in substantially the same manner.

While a specific form of the invention is set forth and disclosed for the purpose of description, it is not intended that the invention be limited thereto, but that certain modifications and changes in the detail structure thereof may be incorporated within the scope of the annexed claims.

What is claimed is:

1. In apparatus for molding tubular articles, a permanent mold, a core extending through said mold, and compressible heat resisting means mounted in the mold adjacent its ends to support said core concentrically within said mold. 90
2. In apparatus for molding tubular articles, a permanent mold, a core extending through said mold, and asbestos rings mounted in the mold adjacent its ends to support said core concentrically within said mold. 95
3. In apparatus for molding tubular articles, the combination with a permanent mold having undercut grooves formed in the inner surface thereof adjacent its ends, beyond the mold cavity, a core extending through said mold, and compressible heat resisting means mounted in said undercut grooves to support said core concentrically with 100 said mold. 105
4. In apparatus for molding tubular articles, the combination with a permanent mold having grooves formed in the inner surface thereof adjacent its ends, beyond the mold cavity, a core extending through said mold, and compressible heat resisting means mounted in said grooves to support 110 said core concentrically with said mold. 115
